Patented Aug. 6, 1912.

UNITED STATES PATENT OFFICE.

JAN HENDRIK WINDEMULLER, OF ROTTERDAM, NETHERLANDS.

FLAME-SPREADER.

1,035,127.

Specification of Letters Patent.

Patented Aug. 6, 1912.

Application filed November 25, 1911. Serial No. 662,477.

To all whom it may concern:

Be it known that I, JAN HENDRIK WINDEMULLER, a subject of the Queen of the Netherlands, and residing at 16 Spoorsingel, 5 Rotterdam, in the Province of Holland, in the Kingdom of the Netherlands, having invented certain new and useful Improvements in and Relating to Flame-Spreaders, do hereby declare that the following is 10 a specification.

This invention relates to a method of spreading flames by retarding the contact of the mixture of air and gas with the combustion air by surrounding the burner tube 15 near the gas issue openings with a screen, ring, cup or shell (hereinafter referred to as a screen) adapted to prevent combustion from taking place within the said screen, the coldest zone of the flame being at the 20 edge of the screen, which thus conducts a minimum amount of heat.

The invention will now be described with reference to the accompanying drawings in which all the figures are vertical sections 25 through the longitudinal axis of the burners.

Figure 1 is an ordinary gas burner to the side of which a partial screen has been applied; Fig. 2 is an ordinary Bunsen burner the upper part of which is provided with a 30 circular horizontal screen; Fig. 3 is a Bunsen mushroom burner having lateral apertures provided with a screen whose vertical section is in the form of a U; Fig. 4 is a mushroom Bunsen burner with lower apertures and provided on one side with a screen 35 of vertical section in the form of a U of comparatively small depth, and on the other side with a screen of similar section but much deeper; Fig. 5 is a Bunsen mushroom 40 burner with lateral apertures and provided with a screen of vertical section in the form of a U of relatively small depth but large diameter. The first four figures illustrate burners intended more particularly for 45 lighting; Fig. 5 represents a burner for heating. Figs. 1 and 2 illustrate ordinary Bunsen burners in which, in the one case a partial screen, and in the other case a circular screen, has been applied. The features of Figs. 1 and 2 are not claimed in 50 this application.

In the drawing 1 is the Bunsen burner, 2 the coldest zone of the flame, 3 is the zone of medium temperature and 4 the zone of maximum temperature of the flame. In 55 Fig. 3 the burner head is mounted upon the

tube 1^a. In Fig. 4 the burner head is mounted upon the burner tube 1^b. In Fig. 5 the burner head is mounted upon the burner tube 1^c.

In Fig. 3, 7 is a mushroom burner having lateral apertures, 8 is a screen of vertical section in the form of a U mounted on the burner.

In Fig. 4, 9 is a mushroom burner having 65 apertures underneath; 10 is a half screen in vertical section having the form of a relatively shallow U. 11 is a half screen the vertical section of which has the form of a U notably deeper than the half screen 10. 70

In Fig. 5, 12 is a mushroom burner having lateral apertures. 13 is a screen the vertical section of which is in the form of a U of comparatively small depth but large diameter.

Experiment has shown that the flame of an ordinary burner expands laterally, and increases in height when a partial screen similar to 5 is provided on the burner 1. It has also been experimentally proved that the 80 expanded flame always assumes a definite form whether the screen has the form shown in Fig. 5 or the forms shown in Figs. 3 and 4. With the same consumption of gas, however, a still more extended form is given to the 85 flame shown in Fig. 5, if it be desired that it should act on a larger surface, as is necessary for certain heating apparatus.

The forms shown in the drawings are 90 solely given as examples, and may assume an infinity of aspects according to the different applications of the invention.

It is proved that by means of the method hereinbefore set forth the saving of gas in heating water is about 25%, in comparison 95 with good ordinary burners, while with incandescent burners of the Auer type a similar consumption of gas produces an increase in illumination varying from 50 to 65%.

I am aware that burners of various types 100 are known in which at the outlet of the burner where ignition takes place an annular ring, flange or cup is provided for directing the flame in an upward direction, e. g. against the mixing chamber or is adapted to be heated by the flame and serve to conduct heat to gas generating chambers so as to assist vaporization. My screen has no analogy with such constructions and its purpose, which is of quite a different nature, is, 105 as already stated, to retard the contact of the combustible fuel with the air for com-

bustion, and displace the initial point of combustion.

Having now described my invention what I claim as new and desire to secure by Letters Patent is:

1. The combination of a burner tube, an enlarged burner head thereon having annularly-arranged discharge openings, and an imperforate cup-shaped shield about said burner head, said shield having a part at one side extending farther below the burner head than a part at the other side, said shield serving to prevent immediate access of air to the burner head, and thereby serving to enlarge the flame.

2. The combination of a burner tube, an enlarged burner head thereon having annularly arranged discharge openings in said enlargement, and an imperforate cup-shaped

shield about said burner head having a free 20 top opening and serving to prevent immediate access of air to said discharge openings and thereby serving to enlarge the flame.

3. In a gas burner, the combination of a Bunsen tube having a gas-discharge opening, and a shield located below and extending outward laterally and widely flaring from the gas discharge opening, to prevent the immediate access of air to the flame.

Dated this 15th day of November, 1911. 30

In testimony whereof I have signed my name to this specification in the presence of two subscribing witnesses.

JAN HENDRIK WINDEMULLER.
